EGG CARTON BASKET

Victor M. Ipsen, Temple City, Calif.

Application February 13, 1956, Serial No. 40,151

Term of patent 3½ years

(Cl. D58—4)

FIG. 1.

FIG. 2.

FIG. 3.

The diametrically opposed sides of the basket from the sides shown in Figures 2 and 3 are identical with Figures 2 and 3, respectively.

The broken-line showing appearing in Figure 2 of the drawing is for illustrative purposes only.

I claim:

The ornamental design for an egg carton basket, substantially as shown and described.
